UNITED STATES PATENT OFFICE

CARMINE FABRIZIO, OF NEW YORK, N. Y.

SELF-FILLING FOUNTAIN PEN

Application filed February 14, 1929. Serial No. 339,904.

My present invention relates to self filling fountain pens and has for its principal object the provision of a simple and novel means for quickly filling an empty fountain pen rapidly with a fresh supply of ink.

Another object is to provide means for pumping ink into a fountain pen and to so arrange the pumping means as to permit it to be locked against accidental movement 10 when not in use.

These and other capabilities will be apprehended as the description proceeds, and it is obvious that modifications may be made herein without departing from the spirit hereof 15 nor the scope of the appended claims.

In the drawings,

Fig. 1 is a side view of my pen,

Fig. 2 is a longitudinal sectional view 20 thereof; shown in pumping position.

Fig. 3 is a similar view showing pumping means in depressed position;

Fig. 4 is a similar view showing pumping means locked; and

Fig. 5 shows the filler end removed from 25 the pen.

In external appearance, my present pen looks like any conventional pen of its type. The barrel 1, is threaded at one end 2, to receive therein the threaded end 3 of a pen 30 holding tube 4, Fig. 5.

The tube 4 is bored to receive therein the pen engaging filler plug 5, which is suitably channelled as at 6 to supply ink from the barrel 1 to the associate pen 7, this latter 35 being locked in the bore 8 in tube 4 in the usual manner by friction.

The plug 5 is provided with a second bore 9 which is located centrally thereof, and into which is mounted an extended open ended tube 10, the bore 11 of which merges into said central bore 9. Thus the bore 9 is virtually extended to the end of the tube 10, which is capped with a flanged disc-like cap 12, the diameter of which is smaller than the bore 45 of the barrel 1 as may be noted in Figs. 2, 3 and 4.

The barrel 1 is provided with a bore 13 which forms the main ink reservoir, and is further provided with a bored closure 14, 50 which is located near the plunger end of the

barrel, and is bored as at 15, to permit the passing therethrough of the stem 16 of a reciprocal piston 17, which piston is made of cork or other suitable resilient substance and which fits the bore 13 snugly.

The barrel 1 is smoothly recessed as at 18, Fig. 2 to receive therein a reciprocal, threaded, closed tubular plunger 19, the threaded interior of which engages with a threaded plug 20 which is formed on the end of the 60 piston stem 16.

A coil spring 21 is mounted so as to encompass the stem 16 with one end resting on the face of the closure 14, and its other end resting under the shoulder formed by the threaded plug 20, thus to normally keep the piston 17 in retracted position, as in Fig. 1.

With the pen empty of ink, and in normally closed position, as in Figs. 1 and 4, the plunger 19 is unscrewed from the closed positions shown in both last noted figures, to the position shown in Fig. 2. This action unlocks the piston and frees it for a reciprocating movement, as the plunger 19 thus becomes an extension of the piston stem 16.

With the plunger unlocked, the point of the pen is then inserted in to a supply of ink and the plunger 19 reciprocated by a plurality of strokes to the limit of its movement, as in Fig. 3, and each reciprocation causes a small 80 amount of ink to be drawn into the reservoir 13, until the reservoir is filled.

Continued pumping action of the piston 17 after the reservoir is filled does no harm, as the excess ink is merely pumped into and 85 out of the pen through the bore 6.

The pen is without valves of any kind and its action in filling is as follows:

When filling, the pen is held in vertical position with the point 7 in the ink supply. 90 A downward pressure upon the plunger 19 expels air from the reservoir 13, release of the plunger causes the spring 21 to retract the piston 17, and ink is drawn upwardly 95 through the bores 6, 9 and 11. The ink thereafter flows down the outside of the tube 10 to lodge in the surrounding chamber, which gradually fills up under repeated short strokes of the plunger. The actual filling operation is very rapid and sure.

After filling the pen as described, the plunger 19 is then screwed back to the position shown in Figs. 1 and 4, and the reciprocating parts are thus locked against accidental movement and loss of ink.

5 It will further be noted that owing to my present feature of shortening the filling stroke, I am able to make the pen with a larger relative ink reservoir capacity, at the same time keeping the length of the pen to its shortest relative length. Further, all operative parts of the device, excepting the non-corrosive piston, are all exterior to the ink reservoir.

10 15 Having thus described my invention what I claim is:

1. In a fountain pen a barrel, a pen point thereon, a means on said pen for conducting ink to the interior of said barrel, a reciprocating piston, slidably mounted in said barrel, a piston rod on said piston, and a means for adjustably varying the length of the stroke of said piston, connected to the outer end of said rod at the outer end of said barrel.

2. In a fountain pen a barrel, a pen point thereon, a means on said pen for conducting ink to the interior of said barrel, a reciprocating piston, slidably mounted in said barrel, a piston rod on said piston, a member, connected to the outer end of said rod, for adjustably varying the length of the stroke of said piston by adjustably varying the position of said member with relation to said end, and a part on said barrel, for limiting the relative position of said member with relation to said end, thereby locking said piston in position in said barrel.

3. In a fountain pen a barrel, a pen point thereon, a means on said pen for conducting ink to the interior of said barrel, a reciprocating piston, slidably mounted in said barrel, a bored closure on said barrel near the outer end thereof, a piston rod on said piston, slidably mounted in the bore of said closure, a threaded end-piece at the outer end of said rod, a threaded member, in adjustable threaded engagement with said end piece, slidably mounted on a part of said barrel at the outer end of the latter and a part on said barrel for limiting the position of said member on said end piece, whereby the length of the stroke of said piston may be adjusted by adjusting the position of said member with relation to said end piece, and said piston being lockable by the abutment of the inner end of said member against said limiting part.

4. In a fountain pen a barrel, a pen point thereon, a means on said pen for conducting ink to the interior of said barrel, a reciprocating piston, slidably mounted in said barrel, a bored closure on said barrel near the outer end thereof, a piston rod on said piston, slidably mounted in the bore of said closure, a

threaded cap at the outer end of said rod, an outwardly open recess in the outer end of said barrel, outwardly of said closure, and an interiorly threaded plunger, in adjustable engagement with said cap, slidably mounted 70 in said recess, whereby the length of the stroke of said piston may be adjusted by adjusting the position of said plunger on said cap, and said piston being lockable by the abutment of the inner end of said plunger 75 against said closure.

5. In a fountain pen a barrel, a pen point thereon, ink conducting means on said pen, extending into the intermediate part of the interior of said barrel, a reciprocating piston, 80 slidably mounted in the part of said barrel outwardly of said means, a bored closure near the outer end of said barrel, a piston rod on said piston, slidably mounted in the bore of said closure, a threaded cap at the outer end of said rod, an outwardly open recess in the outer end of said barrel, outwardly of said closure, and an interiorly threaded plunger, in adjustable engagement with said cap, slidably mounted in said recess, whereby the 85 length of the stroke of said piston may be adjusted by adjusting the position of said plunger on said cap, and said piston being lockable by the abutment of the inner end of said plunger against said closure. 90

6. In a fountain pen a barrel, a pen point thereon, a means on said pen for conducting ink to the interior of said barrel, a reciprocating piston, slidably mounted in said barrel, a bored closure in said barrel near the outer end thereof, a piston rod on said piston, slidably mounted in the bore of said closure, a threaded cap at the outer end of said rod, an outwardly open recess in the outer end of said barrel, outwardly of said closure, an interiorly threaded plunger, in adjustable engagement with said cap, slidably mounted in said recess, whereby to move said piston in one direction, and a resilient means, connected at one end thereof to a part on said barrel and at the other end thereof to a part on said rod, whereby to move said piston in the opposite direction, the length of the stroke of said piston being adjustable by means of the position of said plunger on said cap and 105 said piston being lockable by the abutment of the inner end of said plunger against said closure. 110

7. In a fountain pen of the class described a barrel, a pen point thereon, ink conducting means on said pen, extending into the intermediate part of the interior of said barrel, a reciprocating piston, slidably mounted in the part of said barrel outwardly of said means, a bored closure near the outer end of said barrel, a piston rod on said piston, slidably mounted in the bore of said closure, a threaded cap at the outer end of said rod, an outwardly open recess in the outer end of said barrel, outwardly of said closure, an in- 120 125 130

teriorly threaded plunger, in adjustable engagement with said cap, slidably mounted in said recess, whereby to move said piston in one direction, and a compression spring encompassing said rod and abutting at the inner end thereof against said closure and at the outer end thereof against said cap, whereby to move said piston in the opposite direction, the length of the stroke of said piston being adjustable by means of the position of said plunger on said cap, and said piston being lockable by the abutment of the inner end of said plunger against said closure.

Signed at New York in the county of New York and State of New York, this 13th day of February, A. D. 1929.
